UNITED STATES PATENT OFFICE

JEAN GEDEON MARIE COUDERT, OF ISSY-LES-MOULINEAUX, AND JEAN BAPTISTE TERME, OF ST. ETIENNE, FRANCE

KNITTING MACHINE

Application filed March 11, 1931, Serial No. 521,857, and in France March 11, 1930.

At present the needles of flat knitting machines adapted to work in several colours are usually actuated by a thrust exerted on them by suitably perforated steel blades. The perforations correspond to the needles which have to remain at rest while the imperforate parts of the blades engage and push forward those which have to come into action.

It will readily be understood that the cost of these prepared steel blades is considerable.

The object of the present invention is to enable a standard jacquard mechanism employed in the making of woven fabrics, that is to say a mechanism employing paper or card patterns to be used in such knitting machines without modification. It thus becomes possible to actuate the needles of flat knitting machines by using patterns made of card or paper, without the mode of reading and perforation employed in weaving being in any way changed.

The accompanying drawings diagrammatically illustrate the invention. It will be understood however, that variations in the practical details of embodiment can be employed without the principle of the invention being in any way modified or affected.

Figures 1, 2 and 3 are respectively, sectional side views of three embodiments of the invention.

Referring now to Figure 1, a bed comprises blades such as 1 disposed parallel to one another and equally spaced. They rest on two cradles 2 and 3 which carry spacing blocks 4 and 5. The cradles are connected together at their ends by T irons or the like which hold them parallel and render the whole system rigid.

Between the cradles, that is in the central space, the bed is open to permit the passage of the fingers of the automatic selecting mechanism.

In each space between its parallel blades, and resting on the spacing blocks 4, 5 the bed receives tappets such as 6 each consisting of a rod terminating at the front in a cross-piece 7. At the rear the tappets extend a short distance beyond the bed by an amount proportional to the desired stroke. The rear ends of the tappets rest on a member 8 of

the carriage which effects the feed and retraction of the tappets. The tappets are free in their places and can be displaced in the vertical plane by the fingers of the selecting mechanism.

The carriage consists essentially of an angle bar 8 and a cross bar 9 rigidly connected together. When the carriage advances the bar 8 entrains those tappets which are in their lower positions. When it returns the bar 9 engages the upper parts of the cross pieces of these tappets and returns them. The carriage, as will be seen, surrounds the tappets and is independent of the bed. Its reciprocating movement can be given it by any suitable means. A weight 10 for example can serve to cause its return movement.

The automatic selecting mechanism comprises a fixed shaft 11 on which can pivot a series of beams 12 each having a perpendicular finger 13. To the respective ends of each beam are attached weights *p* and *P*. The former is less than the latter, and must be sufficient to actuate the beam when the weight *P* is lifted. To the latter weight is attached a cord 14 which connects it to the jacquard harness.

The apparatus comprises as many selecting devices as the bed contains tappets, and operates as follows:

A set of pattern cards being in position in the jacquard mechanism and the latter set in action, an upward movement is effected on all the members of the harness corresponding to the holes in the card in action. The corresponding weights *P* are raised. The corresponding weights *p* alone act on the beams which carry them. These swing on the shaft 11 and move to the position indicated in dotted lines at 12', while the fingers 13 pass to the position 13'.

In the original position of the finger its end extends through the central opening into the bed and holds the corresponding tapped 6 raised. During the swinging of the beam which carries it to 13', the finger leaves the tappet which falls freely to the position 6' at the bottom of its seat in the bed.

As will be seen in the drawings all the raised tappets 6 escape engagement by the carriage

when the latter moves forward, while those at 6' are entrained in this movement.

In this way all the selected tappets are moved by the forward stroke of the carriage.

5 In this axial displacement of the tappets their front ends engage and move forward the knitting needles so that they are actuated by the cams in the lock for the purpose of effecting the actual knitting.

10 When the needles have been moved into position, the carriage makes its return movement. The tappets are engaged by the bar 9 and returned to their starting position.

At the end of this movement or even during 15 this movement the jacquard harness returns to its lower position and the tappets are returned to their upper positions by the fingers 13. The cycle then recommences.

The forward movement of the carriage and 20 the selected tappets, and their return movement must take place during the dead portions of the movement of the lock. If the knitting machine requires a movement to and fro of the lock for each row of stitches, the 25 jacquard mechanism must be arranged to act only at every second dead portion of the lock movement.

If the movement of the carriage is derived 30 from the knitting machine the lifting of the jacquard harness must be completed by the moment the forward stroke of the carriage commences. The lowering movement must not take place until the forward stroke is complete. The mechanism therefore works 35 during the movement of the lock.

Referring now to Figure 2, which shows a modified mechanism for lowering the selected tappets, the same reference numbers as in Figure 1 are employed for the same parts. 40 The beams and fingers are here dispensed with and the tappets lifted and lowered directly. The tappets 6 are directly connected by any suitable means such as cords 17 passing over pulleys 18, 19, with the weights P which as before are connected to the jacquard harness by cords 14. There is of course one weight P per tappet. The mode of action of this embodiment will be obvious without further description.

50 Figure 3 shows an arrangement particularly adapted to so-called triple row knitting machines in which in the working position the needles are arranged in the bed in three parallel rows. The first row comprises the 55 needles forming the base fabric. The second row is at the level of the central lock and the third row at the level of the uppermost lock. As each of these positions corresponds to one colour of the design, it is essential to be able 60 to move the needles at will either to the central or the uppermost row. The arrangement shown in Figure 3 enables this to be effected.

Each space in the bed 1, 1' receives two 65 superposed tappets 6 and 15.

The lower tappets 6 are selected and actuated exactly as described above with reference to Figure 1. The upper tappets 15 are selected raised and lowered exactly as described above with reference to Figure 2. 70 They are fed forward and returned by an upper carriage 8'. This carriage is carried forward by the lower carriage 8 when the latter has moved forward by a distance equal to that desired between the central and upper 75 rows of needles.

At the end of the forward movement, the needles moved by the lower tappets form the upper row, those moved by the upper tappets form the centre row, while the needles remaining behind are in a suitable position for knitting the base fabric. 80

It will be understood that each needle must be arranged, as by the provision of the lateral projection 20, so that it can be actuated either 85 by the upper tappet or the lower tappet.

What we claim is:—

1. In a knitting machine the combination of a standard jacquard selecting mechanism employing paper or card patterns exactly as used in weaving, a tappet for moving each needle into position for actuation by the lock, a beam pivoted beneath each said tappet, a finger on said beam positioned to raise the corresponding tappet when said beam is 95 rocket, means for rocking said beams controlled by said jacquard mechanism, and a reciprocating carriage positioned to engage such of said tappets as have not been raised by the corresponding fingers and to clear such 100 as have been raised by the corresponding fingers.

2. In a knitting machine the combination of a standard jacquard selecting mechanism employing paper or card patterns exactly as used in weaving, a tappet for moving each needle into position for actuation by the lock, a tension member attached to each said tappet tending to raise it, means connecting said tension members to said jacquard mechanism 105 whereby selected tappets are prevented from being raised, and a reciprocating carriage positioned to engage such of said tappets as have not been raised and to clear such as 110 have been raised.

3. In a knitting machine the combination of a standard jacquard selecting mechanism employing paper or card patterns exactly as used in weaving, a pair of tappets for moving each needle into two respective positions for knitting operations, said tappets being arranged in two superposed tiers corresponding with said two positions, a beam pivoted beneath each tappet in one of said tiers, a finger on said beam positioned to raise the corresponding tappet when said beam is 125 rocked, means for rocking said beams controlled by said jacquard mechanism, a tension member attached to each tappet of said other tier, means connecting said tension 130

members to said jacquard mechanism whereby selected tappets are prevented from being raised, and a reciprocating carriage positioned to engage such of said tappets as have not been raised and to clear such as have been raised.

4. In a knitting machine the combination of a standard jacquard selecting mechanism employing paper or card patterns exactly as used in weaving, a pair of tappets for moving each needle into two respective positions for knitting operations, said tappets being arranged in two superposed tiers corresponding with said two positions, a beam pivoted beneath each tappet in the lower of said tiers, a finger on said beam positioned to raise the corresponding tappet when said beam is rocked, means for rocking said beams controlled by said jacquard mechanism, a tension member attached to each tappet of the upper of said tiers, means connecting said tension members to said jacquard mechanism whereby selected tappets are prevented from being raised, and a reciprocating carriage positioned to engage such of said tappets as have not been raised and to clear such as have been raised.

5. In a knitting machine the combination of a standard jacquard selecting mechanism employing paper or card patterns exactly as used in weaving, a tappet for moving each needle into position for actuation by the lock, a cross-piece on the front of each said tappet, a reciprocating carriage adapted to feed forward said tappets, means controlled by said jacquard mechanism for moving said tappets into and out of engagement with said carriage in accordance with the pattern, and a cross-bar on said carriage positioned to engage said cross-pieces and retract said tappets on the back stroke of said carriage.

In testimony whereof we have signed our names to this specification.

JEAN GEDEON MARIE COUDERT.
